(57) **CLAIM**

The ornamental design for a measuring and marking angle, as shown and described.

DESCRIPTION

FIG. 1 is a front and left side perspective view of a measuring and marking angle, showing our new design; FIG. 2 is a front view thereof;

FIG. 3 is a left side view thereof;

FIG. 4 is a rear view thereof;

FIG. 5 is a right side view thereof.

FIG. 6 is a top view thereof; and,

FIG. 7 is a bottom view thereof.

The features shown in broken lines in FIG. 4 depict portions of the measuring and marking angle that form no part of the claimed design.
